UNITED STATES PATENT OFFICE.

STILLMAN HOUGHTON, OF WORCESTER, MASSACHUSETTS.

DESIGN FOR A GARTER AND ARMLET-CARD.

Specification forming part of Design No. 5,044, dated June 27, 1871.

To all whom it may concern:

Be it known that I, STILLMAN HOUGHTON, of the city and county of Worcester and Commonwealth of Massachusetts, have invented and produced a new and original Design for Garter and Armlet-Cards, of which the following is a specification:

The nature of my design is fully shown by the accompanying drawing.

It consists of the representation of a garter or armlet, A, in the central part of a dark parallelogram, B, which latter is slightly rounded at the corners, and is inclosed by a border, C, consisting of a light and dark line, as shown. A small spur ornament is placed in each corner of the parallelogram. The figure of the garter or armlet A and other light portions of the device are left of the same color as the card upon which the device is printed, while the parallelogram B and other dark portions of the device are to be of the color of the ink used in printing. In the present instance black ink is used upon white card; but cards and inks of other colors can be used when desired, the form of the device being the same.

I claim as my invention—

The design for garter and armlet-cards, as shown in the drawing and herein described.

STILLMAN HOUGHTON.
